UNITED STATES PATENT OFFICE.

RUDOLPH I. SCHONITZER, OF SPRINGFIELD, OHIO, ASSIGNOR TO THE STEEL WOOL PRODUCTS CORPORATION, A CORPORATION OF OHIO.

METAL-WOOL-MAKING MACHINE.

Application filed February 18, 1922. Serial No. 537,467.

To all whom it may concern:

Be it known that I, RUDOLPH I. SCHONITZER, residing at Springfield, in the county of Clark and State of Ohio, have invented new and useful Improvements in Metal-Wool-Making Machines, of which the following is a specification.

This invention relates to metal wool making machines of the type which operates on a wire as a work piece, and the invention consists in improvements therein, and in combinations and arrangements of parts as will be hereinafter more fully described, illustrated in the accompanying drawings and particularly pointed out in the appended claims, it of course being understood that changes in the form, proportion, size and minor details may be made, within the scope of the claims, without departing from the spirit or sacrificing any of the advantages of the invention.

Figure 1 is a front elevation of a metal wool making machine embodying the features of the present invention.

Figure 2 is a top plan view, on an enlarged scale, of the left hand end of the machine.

Figure 2^a is a similar view of the right hand end of the machine.

Figure 3 is an end elevation of Figure 1 with parts broken away to show certain interior constructions.

Figure 4 is a top plan view, on an enlarged scale, of the means for laterally shifting the storage drum at one end of the machine, parts being broken away to show interior constructions.

Figure 5 is a cross-sectional view on the line 5—5 of Figure 4, parts being broken away to show the clutch shifting device.

Figure 6 is an enlarged detail sectional view of the gear arrangement for actuating the screw employed to laterally shift the storage drum.

Figure 7 is a detail fragmentary sectional elevation of the gear shifting mechanism.

Figure 8 is an enlarged detail sectional view of a portion of the gear shifting mechanism.

Figure 9 is a cross-sectional view on the line 9—9 of Figure 8.

Figure 10 is an enlarged detail plan view of one of the cutter heads.

Figure 11 is a front elevation of Figure

10 with parts broken away to show interior constructions.

Figure 12 is an end view of Figure 10.

Figure 13 is a diagrammatic plan view showing the disposition of the wire as it travels over the work-table from one feed reel to the other.

Figures 14, 15 and 16 are diagrammatic views showing the relation of one of the cutters to the three strands of wire which pass beneath the cutter.

Figure 17 is a diagrammatic view illustrating the action of one of the cutters to prevent abnormal digging into the wire.

Figure 18 is an enlarged front elevation showing one of the presser and guide wheels or rollers, parts being broken away to show the means for vertically adjusting the roller.

Figure 19 is a top plan view thereof.

Figure 20 is a side elevation of Figure 18.

The present machine includes a bed-plate or work-table 1 disposed in a substantially horizontal position and supported by suitable leg standards 2 which may be connected and braced by bars 3 so as to produce a rigid structure. Rising from the top of the table and extending longitudinally thereof is a rib or back plate 4 which is designed to support one or more cutting devices in co-operative relation with the wire from which shavings are to be cut, all of which will be hereinafter explained. Duplicate wire storage drums A and B are disposed opposite the respective ends of the table, and are mounted on the floor in spaced bearing brackets 5 and 6, through the medium of a shaft 7 which extends in opposite directions through the hub 8 of the drum.

The drum is rotatable with the shaft through the medium of a key 9, at the same time the drum is capable of sliding longitudinally upon the shaft for the purpose as will be herein-after explained. Above the drum A is a reel C, and a duplicate reel D is disposed above the drum B. Each reel is rotatably mounted in a bracket 10 extending diagonally upward from the adjacent end of the table.

The wire from which the shavings are to be cut is designated generally by the reference character 11 on the drum A and is wound thereon between the flanges of the drum in any suitable manner. In preparing the machine for cutting shavings from

the ~~reel~~, the free end portion of the wire is led from the drum A beneath the reel C and towards the table 1 and thence completely around the reel C as indicated at *a* in Figures 1 and 13 of the drawings, and around what would be the rear portion of the reel when looking at the front of the machine shown in Figure 1. From the under side of the reel C, the wire portion designated *b* is 10 led across the top of the table and beneath the reel D around the far side thereof and back across the top thereof to the top of the reel C and thence around the bottom of the reel and across the top of the table, as at *c* 15 Figure 13, in parallelism with the strand *b*; thence beneath the bottom of the reel D upwardly around the same back to the top of the reel C; thence down beneath the reel C and across the top of the table, as at *d* in 20 Figure 13, in parallelism with the strands *b* and *c*; thence around the bottom of the reel D and entirely around the same to the bottom thereof and thence, as at *e* in Figures 1 and 13, across the top of the drum B; 25 thence downwardly and around the right hand side thereof and secured thereto in any suitable manner.

From the foregoing description, it will be understood that that portion of the wire 30 which leads directly between the drum A and the reel C on the one hand, and the drum B and the reel D on the other hand, passes entirely around the reel, which produces a sufficiently strong frictional grip between the wire and the reel to rotate the latter when the wire is being wound upon either drum, each drum is of course power actuated in a manner as will be hereinafter described. The relation of the strands *b*, *c* 35 and *d* as they pass across the top of the table 1 is shown in plan in Figure 13. For the support and guidance of the strands as they pass across the table, I preferably provide a guideway in the form of a metal bar 40 12 let into the top surface of the table 1 and provided with parallel grooves or channels to receive the respective wire strands. By reference to Figure 1 of the drawings it will be seen that the bottoms of the reels C and D 45 are disposed in substantially the same plane as the top of the table in order that the strands *b*, *c* and *d* may extend in straight horizontal lines between the reels and the table, thereby to insure a feeding pull upon 50 such strands directly in the direction of their lengths, and insuring the most satisfactory feed of the wire strands across the top of the table.

Inasmuch as the construction mounting 55 and manner of operating the storage drums A and B are identical, a description of one of the drums and its operating mechanisms is deemed sufficient.

Referring now more particularly to Figures 3, 4 and 5, it will be seen that the drum

shaft 7 extends a considerable distance at the rear of the machine, and into a gear casing 13 containing suitable gearing for driving the shaft at different rates of speed, said gearing being in turn driven from a suitable driving wheel 14, such as a pulley wheel in a manner as will be hereinafter explained. As best indicated in Figure 2, it will be seen that the shaft 15 of the driving wheel 14 is 70 provided with a gear 16 within the gear casing 13 and in mesh with the relatively large gear 17 keyed or suitably fixed to a hollow rotatable shaft 18, best shown in Figure 7 of the drawings, which sleeve or shaft is mounted in terminal bearings 19 and 20 75 provided on the ends of the gear casing 13. Loosely mounted upon the shaft 18 so as to rotate thereon are provided the stepped series of gears designated 21, 22, 23 and 24 80 respectively progressing in diameter in the order enumerated. These loosely mounted gears are in mesh with the corresponding gears 21^a, 22^a, 23^a, and 24^a which are keyed or otherwise fixed upon the drum shaft 7. By selectively locking any one of the driving 85 gears 21, 22, 23 and 24 to the driving shaft 18, the drum shaft and consequently the drum may be rotated at different rates of speed.

While any form of gear shift may be employed for selectively locking the driving gears to the driving shaft, a satisfactory arrangement has been shown in Figures 7, 8 and 9 of the drawings. Within the hollow shaft 18 there is mounted an endwise movable shift-bar 25 which is cylindrical in shape so as to have a working fit within the hollow shaft. This shift-bar is provided with a diametrically disposed socket or recess 26 intersecting the exterior of the bar and of a length substantially equal to the length of the hub of any one of the gears 21 to 24 inclusive, each of which hubs being of the same length. Within the socket there is a radially movable key 27 which is under the influence of one or more springs 28 bearing against the back of the socket or recess 26 and against the key 27 with a tendency to normally force the latter radially outward. Each hub of the gears 21 to 24 inclusive is provided with a seat or recess 29 of a size to receive the outer projecting end of the key 27 so as to lock the gear to the shaft 18 for simultaneous rotation. It will, of course, be understood that the shaft 18 is provided with a longitudinal keyway 30 to accommodate the key 27, and said keyway extends through the combined 105 lengths of the hubs of the gears in order that the key 27 may cooperate with any one of the gears to lock the same upon the shaft merely by shifting the shift-bar 25 endwise to selectively bring the key 27 into cooperative relation with the desired gear. The hub of each gear is preferably provided with a 110

bushing 31 keyed thereto as at 32, and the socket 29 is formed in the bushing. Spacing collars 33 are provided between adjacent gears so as to maintain them regularly spaced and also to operate as cams to co-operate with the inclined or cammed surfaces 34 on the end portions of the outer edge of the spring pressed key 27 whereby, when the shift-bar 25 is moved endwise, the spring pressed key 27 will be pushed back into its socket 26 so as to pass beneath or across the spacing collars. Furthermore, this particular construction insures that the key 27 will be centered between adjacent spacing collars and thereby engaged with one gear only, thereby to avoid locking more than one gear at a time to the shaft 18. For convenience in manually shifting the rod or bar 25, there is provided a gear or segment 35 carried by a shaft 36 mounted in a bearing 37 provided upon the inner end of the gear casing and operated by a hand crank 38, which is provided with a spring pressed dog or ratchet 39 cooperating with a segmental rack 40, whereby the handle of the gear 35 may be held at predetermined positions. The gear 35 is in mesh with the rack portion 41 of the shift-bar 25, so that by rotating the gear 35 the shift-bar may be moved endwise so as to bring its key 27 into cooperation with any one of the gears 21 to 24 inclusive. It will here be explained that the portion 41 of the shift-bar 25 is not screw threaded but is provided with a series of parallel circumferential grooves or flanges cooperating with the teeth of the gear 35 in order that the bar 25 may rotate on its axis within the driving shaft 18 without being interfered with by the gear 35 while at the same time maintain the rack 40 in cooperative relation therewith. In order that each of the gears 21 to 24 may be loose upon the driving shaft 18, the shift-bar 25 may be moved to such a position as will bring the middle portion of the key 27 into engagement with one of the spacing collars 33, whereupon the shift bar 25 and the driving shaft 18 will rotate without rotating any of the gears. By reason of this construction and arrangement the rotation of the drums may be stopped without disconnecting the machine from the source of power.

For the purpose of shifting each wire storage drum along its shaft so that the wire may feed to or from the table in a straight line, I have provided the necessary mechanism which is best shown in Figures 3, 4, 5 and 6. Extending in opposite directions from the top of the post 6, and in a horizontal plane, are duplicate arms 42 and 43 provided at their outer ends with open ended tubular slideways 44 and 45 through which work bars 46 and 47 respectively. The ends of the bars 46 and 47 adjacent the drum are connected to a cross-head 48 which has a sleeve 49 rotatably received within a socket 50 on the adjacent end of the hub 8 of the drum. Between the gear casing 13 and the arms 42 and 43 there is a cross-head 51 provided at opposite ends with sockets 52 and 53 receiving the bars 46 and 47 respectively. Suitable set screws 54, or other suitable means, are provided for rigidly connecting the bars 46 and 47 to the cross-head 51. At the middle of the cross-head 51 there is a nut 55 receiving an externally screw-threaded sleeve 56 which is rotatably mounted upon the drum shaft 7 and carries a bevelled gear 57 on the rear end of the screw-threaded sleeve. At this point it will be noted, by reference to Figure 6, that the drum shaft 7 extends through and has a bearing 58 in the inner wall of the gear casing 13. Located between the gear 57 and the gear casing there is a clutch constructed and arranged to selectively drive the screw 56 in opposite directions and from the driving shaft 7. This clutch includes spaced bevelled gears 59 and 60 loosely mounted upon the shaft 7. The gear 59 is held against endwise play along the shaft 7 by being held between the rear end of the screw 56 or the hub of the gear 57 on the one hand, and the ring or collar 61 embracing the shaft 7 and secured thereto in any suitable manner as by a pin or key 62. The gear 60 is similarly mounted and is held between the gear casing 13 or the end of the bearing 58 thereon, and the ring or collar 63 embracing the shaft and held in place by a pin or key 64. Embracing the shaft 7 and located between the gears 59 and 60 is a shiftable clutch member 65 in the form of a sleeve suitably keyed to the shaft 7 so as to rotate therewith but free to slide thereon in the direction of the length of the shaft. The member 65 is secured to the shaft as by keys 65^a and 65^b, held against endwise movement by the collars 61 and 63. One end of the sleeve is toothed as at 66 for engagement with the toothed portion 67 of the hub of the gear 59, while the other end of the sleeve is provided with a toothed portion 68 to engage the toothed portion 69 of the hub of the gear 60. For convenience in shifting the shiftable gear element into and out of engagement with the gears 59 and 60, there is provided a depending yoke or fork 70 which straddles the shiftable gear member 65 and cooperates with the yoke shoe 71 loosely embracing the shiftable member 65 and preferably received within an annular groove or guideway 72 provided on said member 65. The lower end of each arm of the yoke or fork 70 is provided with a slot or bifurcation 73 receiving a stud or projection 74 extending outwardly from the shoe 71, so that by swinging the yoke or fork upon its pivotal support 75, the clutch member 65 may be selectively moved into en-

gagement with the gears 59 and 60. With the shiftable gear member 65 in engagement with the gear 59, the latter will rotate the horizontally disposed gear 76, which gear is 5 mounted upon the upper end of an upright stub shaft 76^a carried in a bearing bracket 76^b provided upon the adjacent wall of the gear casing 13. Another bevelled gear 77 is provided upon the lower end of the stub shaft 76^a and is in mesh with the bottom portion of the gear 57 carried by the screw 56, from which it will be understood that the screw 56 will be rotated in one direction from the shaft 7 as a prime mover. By 10 shifting the shiftable clutch member 65 into engagement with the gear 60, the gear 59 will be loose and the gear 60 will be locked to the shaft and will be rotated thereby. As the gear 60 engages the gear 76 diametrically opposite the gear 59, said gear 76 and also the gears 77 and 57, will be rotated in a direction reverse to that in which they are rotated by the gear 59, wherefore the screw 56 will be rotated in the opposite direction and driven from the shaft 7. It 15 will here be explained that the shiftable clutch member 65 and the toothed portions 67 and 69 of the gears 59 and 60 will have such a relation that the shiftable member 20 will engage either of the gears immediately after it has been disengaged from the other gear so there will be no appreciable loss of time in reversing the rotation of the screw, the purpose of which will be hereinafter described.

By reason of the rotation of the screw 56 in either direction, as just described, it will be understood that the nut 55 and its cross-head 51 will be moved towards and away 25 from the gear casing 13, and by reason of the fact that the bars 46 and 47 connect the cross-head 51 with the cross-head 48 associated with the hub of the storage drum, it will be seen that the drum will likewise be moved towards and away from the gear 30 casing 13.

For automatically actuating the yoke or fork 70 to reverse the rotation of the screw 56, the bar 47 is extended a suitable distance in rear of the cross-head 51 and is provided with trip elements 78 and 79 preferably in the form of sleeves adjustable lengthwise of the bar and secured thereto in any suitable manner as by a set-screw 45 80 carried by each trip and engaging a longitudinal groove 81 in the bar 47. These trip members are disposed at opposite sides of a crank arm 82 depending from the shaft 75 which also carries the depending yoke or fork 70, so that when either of the trip members 78 and 79 engages the crank arm 82, the latter will be swung in the direction of travel of the trip which will of course 55 result in a corresponding movement of the yoke or fork 70 which will in turn affect the

shifting of the clutch so as to change the rotation of the screw 56 and thus reverse the transverse travel or feed of the storage drum.

Inasmuch as the movement of the rod or 70 bar 47, under the influence of the screw 56, is of course slow, and inasmuch as it is desired to quickly shift the clutch, there is provided mechanism for this purpose as best shown in Figure 7 wherein it will be 75 seen that the lower end of the arm 82 is provided with a depending trip 83 having opposite downwardly converging sides or shoulders which cooperate with an upwardly directed spring pressed plunger 84 80 mounted in a socket or casing 85 and provided with upwardly converged walls or shoulders. With the rod or bar 47 traveling in the direction of the arrow on Figure 7, it will be seen that the trip shoulder 83 will travel along the spring pressed plunger 84 and gradually depress the latter until the high points of the cams 83 and 84 come into register, and immediately thereafter the spring pressed plunger will be quickly 85 shot upwardly by the spring 86 and cooperating with the opposite side of the cam portion 83 will quickly throw the arm 82 in the direction of the arrow and thereby quickly shift the clutch. It will of course 90 be understood that the slot, eye or opening 87 in the lower end of the arm 82 and through which the rod 47 passes will be large enough to permit of this movement of the arm on the rod or bar. For convenience in manually operating the crank arm 82, should it be desired to reverse the horizontal travel of the drum before it can be automatically accomplished, a suitable 95 handle 88 is provided upon the arm 82 or the shaft 75, and it is quite apparent that the clutch may be shifted by manually manipulating the handle 88 against the yieldable holding effect of the cam plunger 84.

In the operation of the machine to feed the several strands of wire longitudinally across the table 1, one of the storage drums is set in operation by operating the gear shift to impart any selected rate of speed to the drum shaft 7, whereupon the rotation of the drum, say for instance the drum B, in the direction of the arrow on Figure 1 of the drawings, will cause the wire to be drawn from the reel D to the drum B which will result in the rotation of the reel D in the direction of the arrow and the rotation of the reel C in the direction of the arrow applied thereto, wherefore it will be understood that the three strands of wire b, c and d, leading from the reel C will pass across the table, in the direction of the arrow applied thereto and beneath one or more shaving cutters supported upon the table and in cooperative relation with the tops of the strands of wire as will be hereinafter explained.

5 The strand *d* will pass around the reel *D*, and thence to the drum *B*, while the strands *b* and *c* will pass around the reel *D*, thence back to the reel *C* and thence across the table. The desired tension upon the strands of wire so as to keep the same in a straight and taut condition when traveling across the table 1 is maintained by the friction occasioned by the reels *C* and *D* and the drum 10 *A* and its cooperating parts.

15 It will here be explained that the wire which is passing from the drum *A* to the reel *C* is passing thereto at the rear thereof when looking at the front of the machine 20 shown in Figure 1, and therefore the drum *A* will be at one of its limits and will be bodily moving along its shaft so as to feed the wire in a straight line from the drum to the reel *C*. At the opposite end of the 25 table, the wire will be feeding from the front side of the reel *D* to the drum *B*, and the latter will be traveling along its shaft 7 so that the wire strand *e* will feed from the reel *D* to the drum *B* in a straight line. At 30 the conclusion of unwinding the first lay of coils of wire from the drum *A* to the reel *C*, the travel of the drum *A* along its shaft will be automatically reversed, as hereinbefore explained, and at the same time the 35 bodily travel of the drum *B* will also be reversed in order that the wire may be fed in straight lines from the drum *A* to the reel *C*, and from the reel *D* to the drum *B*. This 40 reversing of the bodily travel of the two drums is automatically kept up until substantially all the wire has been fed from the drum *A*, whereupon the direction of the rotation of the drums is reversed and the wire is then fed from the drum *B* to the 45 drum *A*. It will of course be understood that the rate of travel of the wire may be changed by the gear shift hereinbefore described.

50 In Figure 1 of the drawings I have illustrated a plurality of cutting or shaving devices designated *E*, *F*, *G* and *H*. Any preferred number of cutting devices may be employed, and as they are duplicates in construction and operation a detailed description of one of them is deemed sufficient. By 55 reference to Figures 10, 11 and 12, it will be seen that each cutter includes the substantially horizontal cutter head 89, from which rises a shank 90 that is mounted within a rectangular housing 91 within which the shank 90 is vertically adjustable. Below the cutter head 89 are two duplicate tool holders or cutter holders 92, each of which is provided with a tool receiving seat 60 in which is located the tool or cutter 93. The seat portion of the cutter holder 92 is vertically split or bifurcated, as indicated at 65 94, in Figure 12 of the drawings, and there is a clamping screw 95, extending through the bifurcated portion for the purpose of

70 drawing the sides thereof towards one another so as to clamp the tool 93 rigidly within the holder. The cutter blade 93 has a bevelled cutting edge 97 similar to that of a chisel or the blade of a plane. Each 75 blade is set at an angle to the vertical and the two blades are disposed in reverse relation with their cutting edges located in the space between the tool holders. A tongue and groove connection is provided between each 80 tool holder and the cutter head 89, and a suitable clamping screw 98 is employed for securing the tool holder to the cutter head. The construction shown in Figure 11 includes an undercut rib 99 on the cutter head 89 and a corresponding open ended groove 85 in the tool holder 92. The under face of the cutter head 89, from which the rib 99 projects, is set at an angle to the vertical so as to likewise dispose the tool holder 92 at 90 an angle to the vertical. Extending through the top of the housing 91 there is a rotatable stem 100 swiveled in said top and provided at its upper end with a suitable handle 101. That portion of the stem which extends into 95 the housing is screw-threaded and engages a screw-threaded socket in the top of the shank 90, whereby the latter may be adjustably raised and lowered by manipulation of the screw so as to adjust the cutter 100 blades 93 with respect to the work.

100 The housing 91 is provided at opposite sides with trunnions 102 extending in the direction of feed of the wire and mounted in suitable bearings 103 projecting outwardly from the upstanding rib 4 on the bed or table 1. By this arrangement the housing 91 and the parts carried thereby are pivotally mounted on the axis extending in the direction of the feed of the wire, whereby 105 the cutter head may be tilted transversely of the strands of wire and on the axis afforded by the trunnions 102, for a purpose as will be hereinafter explained. For convenience in adjustably tilting the housing 91 110 and the cutter head, there is provided adjusting mechanism including adjusting screws 104 disposed at opposite sides of the housing and carried by brackets 105 provided upon the upstanding rib 4. Each adjusting screw engages a screw-threaded socket in the bracket 105 and is provided with an annular groove 106 within which is received a stud or projection 107 extending outwardly from the adjacent side of the 115 housing 91. If desired the stud or projection may be equipped with an anti-friction roller. By rotating the adjusting screws 104, the housing 91 may be adjustably tilted on its trunnions 102 to adjust the angular 120 disposition of the cutting edge of each of the cutters 93 with respect to the strands of wire which are traveling beneath said cutting edge, as will be understood by reference to Figures 14, 15 and 16 of the draw. 125 130

ing which are diagrammatic and illustrate the initial and adjusted positions of the cutter edge with respect to the horizontal. In these diagrammatic views, 93 indicates 5 the cutter, 12 the guideway for the wire strands, and *b*, *c* and *d* the wire strands having the arrangement shown in Figure 13. For the first cutting operation, the cutter 93 is disposed with its lower cutting edge 10 in a horizontal position so as to cut shavings from the strands of wire as they travel from left to right or in other words from the reel C to the reel D. As hereinbefore explained, the strand *d* passes from the reel C and 15 around the reel D, as best illustrated in Figure 13, and then as at *e*, said strand portion *d* leads directly to the drum B. Now the other strands *b* and *c*, after having been cut, pass around the reel D and back to the 20 reel C, and thence across the table and become strands *c* and *d*, each of which has been cut along the top thereof, and consequently the cutter, if permitted to remain in its original position, would not engage 25 the cut strands *c* and *d*, as will be understood by reference to the dotted line in Figure 15, wherefore the cutter 93 is tilted vertically into the position shown in full lines in Figure 15 in order that its cutting edge 30 may cooperate with the cut strands *c* and *d* and the uncut strand *b*. After the strand *d* of Figure 15 has been given a second cut, it is of course necessary to effect a further 35 adjustment of the cutter 93 to the position shown in Figure 16, in order that said cutter may cooperate with the strand *d* which was strand *c* and has been subjected to two cutting operations. From this point in the 40 operation of the machine, no further adjustment of the cutting member 93 is necessary, as will be readily understood. When the travel of the wire is reversed, and it is fed from drum B to drum A, it will of course be understood that the opposite set 45 of cutters 93 will be employed, and the tiltable adjustment thereof will be opposite to that indicated in Figures 14, 15 and 16.

By having the cutters 93 of each cutting device disposed reversely, it will be understood that one cutter will be operative in one direction of feed of the wire, while the other cutter will be operative in the other direction of feed of the wire. The cutter which is not in operation is not removed from the 50 holder 92, but is merely backed off far enough to escape the work.

An important feature of the cutting mechanism will be understood by reference to Figure 11 of the drawings wherein it will be seen that the active cutting edge of each cutter is in rear of the vertical center line of support of the cutter with respect to the direction of travel of the wire beneath the cutter, and therefore any yielding of the cutter support under the pulling action of the wire,

will tend to swing the cutting edge of the cutter to the right and upwardly on the arc in the general direction of the travel of the wire and consequently away from the wire instead of being wedged into the wire as 70 would occur if the active cutting edge were disposed in front of the vertical central line of support. The foregoing statement will be better understood by reference to Figure 17 wherein *b* designates the wire to be cut 75 and traveling in the direction of the arrow. 90 designates the cutter head shank or central vertical line of support for the cutter 93 which has its cutting edge in cooperation with the wire. X designates the radius and 80 Y the arc along which the cutting edge of the blade would travel under any tendency of the support to yield in the direction of pull of the wire, wherefore it will be readily understood that the cutting edge of the cutter, under such circumstances, would yield 85 and rise out of engagement with the wire without causing breakage thereof as would occur if the cutter occupied the position designated 90 93.

By reference to Figures 1, 2 and 2^a, it will be understood that the machine or apparatus is designed to be driven from an overhead pulley 108 mounted upon a suitable line shaft 109. A driving belt 110 leads from the 95 driving pulley 108 to one of the pulleys 14 for the driving mechanism of one of the units, and another driving belt 111 extends from the driving pulley 108 to the pulley 14 of the other unit. Inasmuch as the units are 100 driven in opposite directions, in order to change the line of feed of wire, one of the driving belts is crossed, as indicated in Figure 2^a. In order that the two pulleys 14 may be driven from the one driving pulley 108, the latter is a wide faced pulley so as to accommodate the two belts, and one of the pulleys 14 is disposed a suitable distance outwardly from the adjacent casing 13 in order 105 that its belt 110 may travel in a straight line 110 between the pulleys 108 and 14. It will here be explained that when the right hand unit is being driven, the driving portion of the left hand unit is disconnected by manipulation of the crank handle 38, see Figure 7 of 115 the drawings, so as to move the bar 25 until the key member 27 underlies one of the collars 33 and is thereby held out of engagement with any one of the gears 22, 23 and 24, whereby it will be understood that the 120 hollow shaft 18 and the bar 25 may rotate under the action of the pulley wheel 14, while at the same time the gears 22, 23 and 24 may rotate in the opposite direction without being interfered with. By this arrangement, reversing of the direction of travel of the wire may be accomplished without actually disconnecting either of the units from the driving pulley 108. Of course, both 125 units may be disconnected at the same time 130

so that the machine or apparatus may remain idle without stopping the operation of the pulley 108.

An important feature of the present invention resides in the employment of presser and guide rollers at opposite ends of the table and located between the respective reels C and D and the shaving cutters adjacent thereto. These guide and presser rollers are duplicates in construction, and one of them has been shown in detail in Figures 18, 19 and 20, wherein 112 designates a wide faced roller mounted to rotate on a suitable shaft 113 extending through a fork or yoke 114 carried at the bottom of a hollow shank 115, the bore of which is internally screw-threaded for the reception of an adjusting screw 116. The shank 115 is vertically adjustable in a bracket 117 suitably secured to the rib 20 or back plate 4 on the table 1. The body of the bracket has a chamber which is open at the bottom for the introduction of the shank 115 carrying the screw 116. The screw is provided with an annular flange 118, which 25 underlies the under side of the top of the bracket 117 through an opening in which the cylindrical head portion 119 of the screw projects, and is provided upon its outer end with a finger piece 120 knurled or otherwise 30 roughened on its periphery for convenience in manually rotating the screw 116 to raise and lower the shank 115 and thereby adjust the roller 112 with respect to the top of the table. The shank 115 is guided in its vertical movement and is prevented from rotating within the bracket through the medium of a suitable key 121. The purpose of the combined guide and presser roller is to hold the wire down upon the table and insure its 35 most effective feed to the adjacent shaving cutter at one end of the table and from the shaving cutter at the opposite end of the table. It will, of course, be understood that each feed roller is wide enough to extend 40 across the plurality of strands of wire which are passing across the top of the table.

What I claim is:

1. In a metal wool making machine, the combination of a substantially horizontal work-table, means for feeding a single length of wire in substantially parallel strands across the table, and a shaving cutter in co-operative relation with the strands of wire passing across the table.

2. In a metal wool making machine, the combination of a table, means for feeding a strand of wire across the table and including storage drums at opposite ends of and below the table and reels mounted at opposite ends of the table and above the drums, and a shaving cutter in co-operative relation with a wire strand traveling across the table.

3. In a metal wool making machine, the combination of a table, means for feeding a strand of wire across the table and in-

cluding storage drums at opposite ends of and below the table and reels mounted at opposite ends of the table and above the drums, a shaving cutter in co-operative relation with a wire strand traveling across the table, 70 and means for driving one of the storage drums to feed a wire from the other drum to said one drum.

4. In a metal wool making machine, the combination of a table, means for feeding 75 a strand of wire across the table and including storage drums at opposite ends of and below the table and reels mounted at opposite ends of the table and above the drums, a shaving cutter in co-operative relation with a wire strand traveling across the table, 80 means for driving one of the storage drums to feed a wire from the other drum to said one drum, and means for driving the other drum to reverse the direction 85 of feed of the wire.

5. In a metal wool making machine, the combination of a table, means for feeding a wire across the table and including storage drums at opposite ends of the table 90 and reels mounted at opposite ends of the table and above the drums, means for driving one of the drums, means for bodily moving the drums laterally across the reels, and a shaving cutter in co-operative relation 95 with a wire strand passing across the table.

6. In a metal wool making machine, the combination of a table, means for feeding a wire across the table and including storage drums at opposite ends of the table, 100 reels above the drums, means for rotating one of the drums, means for bodily moving the drums across the reels and for reversing the direction of body travel of the drums, and a shaving cutter in co-operative relation 105 with a wire traveling across the table.

7. In a metal wool making machine, the combination of a table, means for feeding a wire across the table and including storage drums at opposite ends of the table, means 110 for driving one of the drums in one direction, means for driving the other drum in the opposite direction, whereby the direction of feed of the wire may be reversed, reels mounted at opposite ends of the table 115 and above the drums, means for bodily moving the drums across the faces of the reels and for automatically reversing the bodily travel of the drums, and a shaving cutter in co-operative relation with a wire 120 passing across the table.

8. In a metal wool making machine, the combination with a table and a shaving cutter, of means for feeding a wire across the table in co-operative relation with the 125 cutter and including storage drums at opposite ends of the table, means for driving each drum, each of said means including a shaft for rotating the drum, a screw threaded sleeve rotatable upon the shaft, a nut 130

- mounted to travel upon the screw threaded sleeve and connected with the drum to move the latter along the shaft, and means for automatically reversing the direction of rotation of the screw threaded sleeve to reverse the direction of the bodily travel of the drum on the shaft.
9. In a metal wool making machine, the combination with a table and a shaving cutter, of means for feeding a wire across the table in co-operative relation with the cutter and including storage drums at opposite ends of the table, means for driving each drum, each of said means including
- 15 a shaft for rotating the drum, a screw threaded sleeve rotatable upon the shaft, a nut mounted to travel upon the screw threaded sleeve and connected with the drum to move the latter along the shaft, and means
- 20 for automatically reversing the direction of rotation of the screw threaded sleeve including a reversing clutch driven by the shaft to reverse the direction of the bodily travel of the drum on the shaft.
- 25 10. In a metal wool making machine, the combination of opposite wire storage drums, a shaving cutter mounted to operate upon the wire feeding between the drums, each drum having a drum shaft on which it is
- 30 mounted to slide, a driving shaft for each drum shaft, clutch mechanism between each driving shaft and its co-acting drum shaft whereby the drum shaft may be driven or be permitted to idle with respect to the
- 35 drive shaft, means actuated by the rotation of the drum shaft to slide the drum along the shaft and including a reversing clutch, and means controlled by the sliding movement of the drum to actuate the clutch for
- 40 reversing the travel of the drum.
11. In a metal wool making machine, the combination with means for feeding a single length of wire in substantial parallel strands, of a shaving cutter in cooperative relation with the several strands of wire and mounted for tiltable adjustment to accommodate the cutting edge of the cutter to the cut and uncut strands of wire.
12. In a metal wool making machine, the combination with means for feeding a single length of wire in substantial parallel strands and for reversing the direction of travel of the strands, of a shaving cutter mounted for tiltable adjustment in opposite directions to
- 55 accommodate its cutting edge to cut and uncut strands of wire.
13. In a metal wool making machine, the combination of a work table, means for feeding a single length of wire in substantially parallel strands across the table with all of the strands traveling in the same direction, of a shaving cutter having its cutting edge extending transversely across the several strands, and means for adjustably tilting the cutting edge of the cutter to ac-

commodate the cutter to cut and uncut strands.

14. In a metal wool making machine, the combination of a table, means for feeding a single length of wire in substantially parallel strands across the table with all of the strands traveling in the same direction, means for simultaneously changing the direction of travel of all of the strands, a shaving cutter in cooperative relation with the several strands, and means for tiltably adjusting the cutting edge of the cutter in opposite directions to accommodate the cutter to cut and uncut portions of the wire strands and also to the direction of travel of said strands.

15. In a device of the class described, a support for the passage of wire, means for sustaining a supply of wires and for drawing a plurality of them in one direction over the support, a cutting tool adjacent to the support engaging the wires traveling over the support and tensioning means on the side of the cutting tool from which the wires are delivered adapted to engage said plurality of wires placed side by side and passing in engagement with the tool to sufficiently tension said wires passing the tool so that the single tool may simultaneously cut from each wire a steel wool shaving.

16. In a device of the class described, a support for the passage of wire, means for sustaining a supply of wires and for drawing a plurality of them in one direction over the support, a cutting tool adjacent to the support engaging the wires traveling over the support and tension creating rollers on the side of the cutting tool from which the wires are delivered adapted to engage said plurality of wires placed side by side and passing in engagement with the tool to sufficiently tension said wires passing the tool so that the single tool may simultaneously cut from each wire a steel wool shaving.

17. In a device of the class described, a support for the passage of wire, means for sustaining a plurality of wires, means for drawing said wires in one direction over the support, a cutting tool adjacent to the support engaging the wires traveling over the support, tensioning means on the side of the cutting tool from which the wires are delivered adapted to engage said plurality of wires placed side by side and passing in engagement with the tool to sufficiently tension said wires passing the tool so that the single tool may simultaneously cut from each wire a steel wool shaving, and automatic means reciprocating the wire sustaining device across the path of travel of the wires whereby the drawing means always delivers the wires parallel to each other to the tensioning means.

18. In a device of the class described, a

support for the passage of wire, a reel for sustaining a plurality of wires, means for drawing said wires in one direction over the support, a cutting tool adjacent to the support engaging the wires traveling over the support, tensioning means on the side of the cutting tool from which the wires are delivered adapted to engage said plurality of wires placed side by side and passing in engagement with the tool to sufficiently tension said wires passing the tool so that the single tool may simultaneously cut from each wire a steel wool shaving, and automatic means reciprocating the wire sustaining reel across the path of travel of the 15 wires whereby the drawing means always delivers the wires parallel to each other to the tensioning means.

RUDOLPH I. SCHONITZER.
